UNITED STATES PATENT OFFICE.

TOM L. JOHNSON, OF CLEVELAND, OHIO.

SIGNAL FOR TRAM-CARS.

SPECIFICATION forming part of Letters Patent No. 329,566, dated November 3, 1885.

Application filed May 27, 1884. Serial No. 132,940. (No model.)

To all whom it may concern:

Be it known that I, TOM L. JOHNSON, a citizen of the United States, residing at Cleveland, in the county of Cuyahoga and State of Ohio, have invented certain new and useful Improvements in Head - Light Signals for Tram-Cars, of which the following is a specification.

My invention is an improved head-light signal for tram-cars, constructed as fully set forth hereinafter, so as to be capable of being varied in order to make a large number of distinctive signals, and to provide means whereby sufficient light is afforded upon the platforms to facilitate the operations of the conductor and driver without the necessity of employing a separate lamp for this purpose.

In the drawings, Figure 1 is a front view representing my improved head-light signal for tram-cars. Fig. 2 is a transverse vertical section of Fig. 1, showing the signal arranged upon a car. Fig. 3 is a section on the line 1 2, Fig. 1. Fig. 4 is a perspective view of the frame, and Figs. 5 and 6 are views illustrating modifications.

In cities where different lines of cars use a common track or are stationed at a common center it is important to have some visible distinction, especially at night, whereby passengers and others can determine the lines to which the various cars belong. This has been done by providing the cars with head-lights or signal-lights of different colors; but as only primary colors can be used this mode of distinguishing the cars is of course limited and fails to serve the purpose in large cities. Furthermore, in the suburbs of large cities and in small towns where the streets are not very well lighted, it is desirable to provide means whereby the drivers can distinguish the passengers, or the conductor inspect his money in making change, &c., and this has usually necessitated the employment of special lamps for the purpose.

My invention consists of a head-light signal in which the field light or glass is combined with one or more bull's-eyes in such manner that various combinations may be made, so as to afford distinctive signals for a large number of separate lines, and at the same time illuminate the platform, so as to facilitate the operations of the driver or conductor.

In constructing my improved head-light signal I generally make the field-glass A of transparent glass, and combine therewith one or more bull's-eyes, B, arranged in respect to the field-plate so as to cover but a portion of the latter, the glass composing the bull's-eye being colored, or, as shown in the drawings, the field-glass beneath the bull's eye being colored, so that the head-light presents a combination of colors, whereby it may be readily distinguished from those in common use, consisting each of a single color, or from other head-lights in which there is a different arrangement of field-glass and bull's-eyes. Thus the field-glass A may be oval with the bull's-eye B in the center, as shown in Figs. 1, 2, and 3; or the field-glass may be circular, as shown in Fig. 5, with two or more bull's-eyes arranged thereon; or it may be diamond-shaped with a different arrangement of bull's-eyes, as shown in Fig. 6. In any event I am enabled by the relative arrangement of the field-plate and bull's-eyes to secure a large number of distinct signal-lights, in which the colored rays are intensified by the action of the lens, so as to be visible from a considerable distance, while the transparent field-glass permits the rays of light to pass directly to the platform without obstruction or absorption, and affords the requisite light for the conductor or driver without the employment of a separate lamp for the purpose.

The field-glass and bull's-eye may be secured in their proper relative positions in any suitable manner; but I prefer to use a frame, D, recessed to receive the field-glass, which is secured in position by putty or cement, and formed in one piece with one or more internal frames, f, held in position in respect to the main frame by ribs e. The frames f are contracted toward the front, so as to permit the bull's-eyes B to be inserted from the rear, after which the insertion and securing of the field-glass serves as a means of holding the bull's-eyes securely in their places.

When desired, the field-glass may be made the means of displaying the name of the car, line, or route, or other matter or symbols.

The frames above described, cast in one piece, may be made at a comparatively slight expense, secure a support for the glass, and the ribs e, extending over the field-glass, serve to

protect and guard it without materially obstructing the light.

It will be seen that in the construction of frame described the inner frames, *f*, are in 5 advance of the outer frame, so as to support the bull's-eyes in a plane in advance of the field-glass.

The position of the signal-light in respect to the wall of the car is illustrated in Fig. 2, 10 in which *X* designates the wall of the car, and *I* the case of the lantern containing the usual lamp, *J*.

I am aware that a reversible glass ball has been placed in front of a head-light for locomotives; but my invention is distinguished 15 from such an arrangement by the fact that I use a bull's-eye lens in connection with a field-plate less in area than the latter and secured in the supporting-frame of the field- 20 plate.

Without limiting myself to the precise construction and arrangement of parts shown, I claim—

1. A head-light signal for tram-cars, consisting 25 of a field-plate of glass of one color covering the whole field, and one or more fixed bull's-eyes or lenses less in area than the field-plate, and fixedly retained in front of and in proximity to the field-plate, substantially as 30 set forth.

2. A tram-car lamp-signal frame holding within its border a smaller frame, the large frame constructed for holding a field-glass and the smaller frame for holding a glass bull's- 35 eye, the planes of the two glasses differing, substantially as and for the purpose set forth.

3. A tram-car signal consisting of a frame supporting a field-glass, lettered or marked as set forth, and a smaller inner frame supporting a bull's-eye in front of the field-glass and 40 of a different color, substantially as specified.

4. The combination, with the lamp of a tram-car, of a signal head-light consisting of a field-glass covering the whole field, a supporting-frame, and one or more smaller bull's-eyes 45 supported fixedly by the frame in front of and in close proximity to the field-glass, substantially as set forth.

5. A frame for the head-light signal of tram-cars, consisting of an outer frame adapted to 50 receive and hold the field-glass, and a smaller inner frame adapted to support the bull's-eye, and connections between the two, substantially as set forth.

6. A frame for a signal-glass, consisting of 55 an outer frame and an inner frame fixedly supported in a position in advance of the former, substantially as set forth.

7. A tram-car signal provided with a frame consisting of an inner and an outer frame 60 fixedly connected in one piece and adapted to support the field-glass, and a bull's-eye in front of the field-glass, substantially as specified.

In testimony whereof I have signed my 65 name to this specification in the presence of two subscribing witnesses.

TOM L. JOHNSON.
